UNITED STATES PATENT OFFICE

DREW HEAD, OF CHICAGO, ILLINOIS

INTERNAL COMBUSTION MOTOR

Application filed February 24, 1930. Serial No. 430,570.

This invention relates to improvements in internal combustion motors, and more particularly to a novel design for the piston and cylinder head of such motors calculated to 5 improve their efficiency and performance.

With the development of the high speed, high compression motor for automotive uses, the need for more complete and perfect combustion of the explosive mixture in the cylinder has been recognized and considerable effort has been directed toward designing the combustion chambers so as to eliminate the various factors believed to contribute to power loss in the cylinder.

15 The object of the present invention is to provide a design for the combustion chamber and piston calculated to further improve the conditions of combustion within the cylinder through increased turbulence of the explosive mixture during the intake and compression strokes, thereby creating a more homogeneous mixture uniform and slower burning, and consequent reduction in detonation and resulting reverberation.

25 Considering the L-head type of motor, that is, the type in which the inlet and exhaust valves are located on the same side of the cylinder, the combustion chamber is considered to include all of the space above the piston 30 when the same is at top dead center, the volume of this space bearing a predetermined ratio to the total displacement of the cylinder as a factor in determining the maximum compression. These factors, however, have been 35 more or less standardized in motor design, and, therefore, the present disclosure is concerned more with the shape and conformation of the surfaces of the combustion chamber.

40 A preferred embodiment of my invention is shown in the accompanying drawing of a typical L-head motor in which,

Figure 1 is a view in vertical section through one of the cylinders of the motor as 45 taken on line 1-1 of Figure 2, and

Figure 2 is a view in cross section through the head of the motor as taken on line 2-2 of Figure 1.

Following the standard design of motors 50 of the L-head type, the cylinder 1 is offset to

one side of the motor bloc, and in the cylinder is a piston 2 carried at the upper end of a connecting rod 3. On one side of the cylinder are the inlet and exhaust ports 4 and 5 which connect with the inlet and exhaust manifolds 55 respectively. The inner ends of the ports open upwardly and form the seats for the inlet and exhaust valves 6 and 7, their stems extending downwardly through vertical bearings 8 and connected with the usual timing 60 mechanism.

As is customary in motor construction, a hollow casting or head 9 is bolted to the cylinder bloc 1, and extends over the cylinder and the valves forming the combustion chamber. In this instance the bottom surface of the head is formed, a wall 10 having a dome-shaped segment 10a extending over the valve ports, and an inverted dome-shaped or convexed segment 10b over the cylinder and projecting downwardly into the upper end of the same in concentric relation to its walls. The wall 10 is cast integral with the marginal portions 11 of the head which bear flatwise against the top of the cylinder bloc with their 75 inner edges describing the limits of a symmetrical pattern 12 (Figure 2) encircling the top of cylinder and the valve ports.

At the top of the dome-like segment 10a of the wall 10 and in vertical alignment immediately above the valves is a threaded bore in which the spark plug 13 is mounted, with its terminal points projecting just within the combustion chamber.

Referring to the piston 2, the same is of standard design and construction, except for the head 2a which has the form of a semi-spherical concave wall complementing the convex segment 10b of the cylinder head. In the top dead center position these complementing concavo-convex surfaces of the piston and cylinder heads are separated by a narrow clearance space 14 which forms a part of the combustion chamber.

In accordance with the well known principle of operation of the four cycle internal combustion engine, the explosive mixture is drawn into the cylinder during the intake (down) stroke of the piston with the opening of the inlet valve at the commencement of 100

each cycle, and during the compression (up) stroke the charge is compressed and then ignited just in advance of the completion of the compression stroke. Without some means 5 within the combustion chamber for breaking up the stream of incoming mixture, it ordinarily tends to become more or less stratified or divided, with the result that the mixture burns more rapidly in some regions of the 10 combustion chamber, and under compression explodes with a sudden detonation; while other portions burn more slowly due to being diluted by the inert burned gas remaining after the previous exhaust stroke.

15 However, if a definite turbulence is set up in the combustion chamber as the incoming mixture is drawn in, more uniform conditions are established, which is reflected in a more even rate of flame propagation and 20 smoother delivery of power to the piston.

In the present design this is promoted 25 by the complementary concavo-convex faces of the piston and cylinder heads, in that the stream of incoming mixture on entering the cylinder come in contact with these rounded surfaces and is broken up into many streams flowing in different directions, thus setting up a general turbulent condition and thus distributing the mixture uniformly throughout 30 the combustion space. This is true during the compression as well as the intake stroke, inasmuch as the gases are compressed between two oppositely rounded surfaces, and consequently greater efficiency and smoother 35 power impulse is to be expected.

I claim as my invention:

1. In an internal combustion engine, the combination of a cylinder having a head provided with a substantially semi-spherical 40 portion projecting into said cylinder and presenting an uninterrupted convex surface, and a piston in said cylinder having a concave head complementing the convexity of said cylinder head.

45 2. In an internal combustion engine, the combination of a cylinder having a head depressed into said cylinder in the form of a semi-spherical wall presenting an uninterrupted convex surface arranged symmetrical- 50 ly with respect to the axis of the cylinder, and a piston having a concave head complementing the convexity of said cylinder head.

55 3. In an internal combustion engine, the combination of a cylinder; a piston in said cylinder having a head provided with a sub- 60 stantially semi-spherical depression symmetrically disposed with respect to the axis of said cylinder, a cylinder head forming a combustion chamber communicating with the upper end of said cylinder and having a semi- 65 spherical convex portion complementing said concave depression in said piston head and providing an uninterrupted surface project- 70 ing axially into said cylinder in close prox- 75 imity to the concavity in the head of said pis-

ton to form a narrow clearance space communicating with said combustion chamber when the latter is in top dead center position.

Signed at Chicago, Ill., this 21st day of February, 1930.
